COMBINED EMERGENCY SIGNAL TRANSMITTER AND RACK THEREFOR

Charles A. Koster, Phoenix, and Wayne E. Perry, Tempe,
Ariz., assignors to Aero Electronics Development Co.,
Inc., Tempe, Ariz.

Filed Apr. 6, 1973, Ser. No. 348,729

Term of patent 14 years

Int. Cl. D29—02; D14—03
U.S. Cl. D10—106

FIG. 1 is an exploded view of a combined emergency signal transmitter and rack therefor showing our new design;

FIG. 2 is an exploded view from the opposite side;

FIG. 3 is a fragmentary exploded view as taken from the right side thereof; and

FIG. 4 is a fragmentary exploded view as taken from the bottom thereof.

The transmitter is fragmentarily shown in FIGS. 3 and 4 for convenience of illustration.

We claim:

The ornamental design for a combined emergency signal transmitter and rack therefor, as shown and described.
